WASHING MACHINE

David A. Meeker, Troy, Ohio, assignor to The
Hobart Manufacturing Company, Troy, Ohio,
a corporation of Ohio

Application November 3, 1930, Serial No. 492,915

27 Claims. (Cl. 141—9)

This invention relates to washing machines.

One of the principal objects of the invention is the provision of a washing machine of simple and compact construction which may be readily installed for use, is capable of rapid operation while requiring but little attention from the operator, and provides long life for the operating parts.

Another object of the invention is the provision of a washing machine having a compact pumping unit of few parts constructed to effectively prevent leakage adjacent the pump shaft.

Still another object of the invention is to provide a small and compact washing machine of this character, such as one particularly adapted for fountain, restaurant or domestic use, and which is provided with a supporting table constructed to permit ready assembly, convenient and easy operation, and to effectively restrain leakage from the assembled machine to give a cleanly and sanitary installation.

Other objects and advantages of the invention will be apparent from the following description, the accompanying drawings and the appended claims.

In the drawings, which disclose a preferred embodiment of the invention—

Fig. 1 is an elevational view of a washing machine constructed in accordance with this invention; some of the parts being broken away for clearness of illustration;

Fig. 2 is a sectional view taken on the plane of the line 2—2 of Fig. 1;

Fig. 3 is a horizontal sectional view taken on the plane of the line 3—3 of Fig. 2;

Fig. 4 is a detail of the rotary wash arm;

Fig. 5 is an enlarged vertical section taken on the plane of the line 5—5 of Fig. 1;

Fig. 6 is a fragmentary sectional view of a portion of Fig. 5, showing the parts in operating position;

Fig. 7 is a sectional view taken on the plane of the line 7—7 of Fig. 5;

Fig. 8 is a fragmentary view in elevation of a portion of the pump impeller;

Fig. 9 is a detail view in elevation looking upwardly toward the motor switch and rinse valve;

Fig. 10 is a sectional view of the rinse valve and associated parts;

Fig. 11 is a detail view taken substantially on the line 11—11 of Fig. 1 and showing the interlock between the cover member and the control shaft; the parts being shown with the cover closed and control member in neutral position;

Fig. 12 is a view similar to Fig. 11 and shows the control shaft in washing position;

Fig. 13 is a view corresponding to Fig. 11 and shows a control shaft in the rinse position;

Fig. 14 is a detail of the control shaft; 5

Fig. 15 is a plan view of the frame of the supporting table for the washing machine;

Fig. 16 is a plan view of the covered frame which provides a support for the washing machine; 10

Fig. 17 is a view in perspective of the washing machine and table assembled; and

Fig. 18 is a sectional detail of a portion of the wash arm and supporting member.

The drawings, in which like characters of reference designate like parts throughout the several views thereof, illustrate a washing machine having an open top tank 10 comprising a washing compartment, and a well or sump 11 which is preferably formed as an integral part of the tank 10 to provide a reservoir for the collection of a quantity of wash water. The tank 10 is covered by a unitary casing or cover consisting of a fixed portion 13 which is attached to the tank, and a movable portion 15 which is pivoted from and is adapted to swing within the fixed portion. The fixed and movable cover portions each comprise parallel plane surfaced side walls 13^a and 15^a respectively and curved walls 13^b and 15^b respectively of substantially 20 semi-cylindrical form. Adjacent side walls of the portions are provided with pivot bolts 16 so that the movable portion 15 may be swung from an open position in which it is telescoped within the fixed portion to a closed position in which it is extended from the fixed portion and, with the fixed portion, provides a water-tight enclosure for the open top tank 10. The fixed portion has a lower edge which is attached to the tank top, and which cooperates with the top of a supporting table to provide a water-tight construction, and has an inturned lip 13' on the under side of the curved wall adjacent the upper edge thereof. The movable portion 15 is provided with an outwardly extending flange 15' at 30 the edge of the curved wall telescoped within the fixed portion which serves with the lip 13' to restrain the escape of liquid from between the cover portions. The placing of the pivot bolts 16 is such that the cover portions are not concentrically mounted but are offset an amount to permit the flange 15' to swing out of contact with the curved wall of the fixed portion of the cover until the cover is practically closed. Such an arrangement permits the movable cover to 35

40

45

50

55

swing in a substantially friction-free manner until it closes over the tank 10 at which time the flange 15' comes into contact with the curved wall of the fixed cover to restrain the passage 5 of washing water therebetween. Any small amounts of water that may pass beyond the flange are directed by the adjacently positioned lip 13' into the trough formed between the curved wall of the movable cover and the extending flange 15'. Any water collecting here 10 drains to one side or the other of the movable cover and then passes downwardly between the overlapping side walls of the cover portions into the tank 10.

15 The pivot bolts 16 are supported to provide free pivotal movement for the movable cover 15. Hub members 12 are provided on the side walls of the fixed cover and are positioned as by means of rivets on the turning axis of the cover. The 20 hub members comprise metal plates having inwardly extending central bosses in which are provided axially aligned bolt holes. Similarly shaped hub members 14 are provided on the movable cover and are positioned with outwardly extending 25 central bosses having aligned holes of such diameter as to receive a shouldered portion of the bolt 16. The length of the boss on each of the hub members 14 is greater than the thickness of the side wall 15a, and as the side wall 15a is 30 fastened snugly to the flange of the member 14, the side wall is thus held in spaced relation within the adjacent side wall 13a of the stationary cover member. In addition, the length of the larger diameter portion of the bolt 16 between 35 its head and the shoulder which abuts against the member 12 is greater than the length of the boss of the member 14, so that the shoulders of the bolt 16 may be drawn tight against the hub member 12 without binding the member 14, 40 thus providing a substantially friction-free pivotal mounting. The clamping engagement of the bolt shoulders on the members 12 effectively seals the bolt openings against passage of washing water to the exterior of the machine at this point.

45 A centrifugal pump 17 is attached to the tank to provide a circulation of wash water from the well or sump 11 to suitable wash nozzles within the tank 10 and is mounted beneath the portion 10 and at the side of the well portion 11. The pump 50 is driven by an electric motor 18 which is supported from the housing of the pump. The pump and tank are provided with aligned openings; the central intake opening 20 of the pump communicating with the interior of the well 11 through 55 an opening 11', while the tangentially positioned discharge outlet 22 of the pump is aligned with a central opening 22' in the bottom of the tank portion 10 and is attached thereto by means of a threaded sleeve 23. A rotary wash arm 24 is 60 suitably mounted for free rotational movement within the tank 10 and is connected to the discharge of the pump to supply sprays of wash water within the casing. The wash arm 24 has incorporated in it pipes and jets for the supply 65 of rinse water. A suitable trackway 26 is provided within the machine for the reception of racks of dishes or other articles to be washed.

70 The pump 17 and motor 18 form a unit in which a common shaft 28 is provided. The shaft 28 carries the motor armature 29 at one end and has mounted upon its opposite end, within the pump housing, an impeller 30. The impeller, which comprises a disc-like member having suitable water circulating vanes provided thereon, is 75 arranged so that it may move axially with re-

spect to the pump housing; this movement being provided to aid in maintaining a water-tight joint at the point of entrance of the shaft 28 within the pump housing without the use of a stuffing box. The impeller is preferably fixed to the shaft 5 28 and is shown held to the shaft 28 by means of a key 31, and by a nut 32 which engages the threaded end of the shaft. The housing 33 of the pump is preferably a casting of volute form having an open side, defined by the circular wall 10 34, which is closed by an extending portion 35 of the frame 36 of the motor. In assembling the motor and pump the impeller 30 may be attached to the end of the shaft 28 protruding from the motor, and the motor and assembled impeller 15 20 may then be attached to the pump housing 33, as by means of bolts 38, to provide a compact pumping unit. The pumping unit is securely held to the tank 10 by being bolted to the reservoir portion 11, and also by being secured directly to 25 the bottom of the tank 10.

The pump housing 33 is attached to the side wall of the reservoir 11 by means of the two screws 40 which are shown diametrically spaced one above the other, and is positioned so that the central intake opening 20 of the pump will coincide with the opening 11' of similar shape in the wall of the reservoir 11. A suction fitting 43 is attached to the inner side of the reservoir wall and is secured thereto in alignment with the opening 41 by means of the two screws 44 which are also diametrically spaced, and stand at right angles to the pump housing screws 40. Such an arrangement of attaching screws permits the parts to be readily assembled. The 30 suction fitting is preferably a hollow casting of elbow shape having a passage opening downwardly and terminating a relatively short distance from the bottom wall 46 of the reservoir 11. Upon operation of the pump, wash water, which 35 is maintained at a suitable level in the reservoir 11, is drawn through the suction fitting 43 and communicating openings 11' and 20 to the interior of the pump for discharge from the pump outlet 22. Suitable means are provided for 40 maintaining the wash water level in the reservoir and, as shown, comprise an overflow pipe or stand pipe 47 in the form of a cylindrical tube having a tapered lower end portion 48 which is adapted to be received within a similarly tapered opening 50 provided in a depending boss 49 formed in the bottom wall 46 of the well. The boss 49 terminates in a threaded connection 50 to which a suitable drain pipe (not shown) may be attached. The upper open end of the stand pipe 47 is provided with a suitable handle 51 by which the stand pipe may be grasped when it is desired to drain the reservoir by removing the pipe. During 55 operation of the machine wash water is maintained in the reservoir at the level of the open upper end of the stand pipe. If the quality of water within the reservoir 11 exceeds the level of the open end of the stand pipe 47, as by the addition of rinse water, the excess is drained away through the pipe 47 and carries with it any surface accumulation of grease or like substance that may have been washed from the dishes. The accumulation within the sump 11 of large particles of waste materials washed from the dishes is prevented by the provision of a suitable 60 strainer 52 which is positioned to overlie the open top of the sump. The strainer is provided with a suitable lifting handle and is flared upwardly and outwardly at 53 adjacent the outer edges so as to form a receptacle of cup-like form having a 65 70 75

peripheral edge which is adapted to rest upon the bottom face of the tank 10 adjacent the sump.

At the end of the washing period when it is desired to clean the machine, the reservoir 11 is drained by simply removing the pipe 47 so that the liquid contained therein may flow freely through the connected drain pipe. Before again placing the machine into service the stand pipe 47 is placed in assembled position. Means are provided to aid in guiding the tapered end 48 of the pipe into the receiving socket of the member 49. As shown, the suction fitting 43 is provided with spaced ribs 54 which extend substantially vertically and define a curved face or channel 55 positioned in substantial alignment with the opening in the member 49. The pipe 47 may be readily positioned by lowering it within the reservoir until the end portion 48 comes into contact with the curved channel 55 whereby it is guided in its downward movement into the recessed opening in the member 49.

The extending portion 35, which comprises an integral part of the motor frame, is provided with spaced disc-like walls 57 and 58. The wall 57 of the motor frame carries a bearing 59 for the support of one end of the motor armature 28; the other end of the shaft being supported by a bearing carried by the motor frame in the usual manner. The wall 58 is provided with a sealing member 60 to restrain leakage along the passage through which the shaft 28 passes for attachment of the impeller 30. The sealing member 60, which is of bronze or other suitable material, provides a free passage for the shaft 28 and is formed on the side of the wall 58 within the pump housing with an extending annular flange or face. Sealing means are provided within the pump housing to cooperate with the sealing member 60 and prevent the passage of leakage water from the housing along the shaft while the pump mechanism is at rest, and means are provided which are operable during pumping to maintain a subatmospheric pressure within the pump housing adjacent the shaft passage so that leakage is restrained during operation of the pump. The hub portion of the impeller may function as a sealing means or, as shown, a washer 68 may be provided of some suitable hard material such as stainless steel, which is held on the shaft between a shoulder 69 and the hub portion 70 of the impeller and during periods of rest bears against the sealing member 60 to close the shaft passage against leakage. Resilient means such as the spring 72, shown positioned on the shaft 28 between the motor armature 29 and suitable washers 73 which bear against the wall 57, provides a thrust on the shaft which tends to move the shaft 28 to the right so that the washer 68 will be held in sealing contact with the face 75 of the bearing 60. Means are incorporated in the construction of the impeller to create a force upon rotation that will move the impeller and its associated parts to the left (as viewed in Fig. 5), so that during normal operation of the pump the washer 68 will be maintained out of contacting engagement with the member 60. During operation of the pump the impeller thrust overcomes the tension exerted by the spring 72 and the washer 68 is drawn away from the sealing member 60. When the motor circuit is opened after use, and at some point during the time that the impeller and its shaft are slowing down, the tension of the spring 72 overcomes the thrust imparted by the impeller so that the washer 68 is moved into contact with the face 75 of the

sealing member and is thereby ground into a sealing fit each time the motor circuit is opened after operation of the pump. As the washer 68 is maintained out of contact with the face of the sealing member during normal operation wear 5 on these parts from frictional contact is reduced so that long life of the operating parts is assured, while reducing the power consumption due to minimizing of the friction of operation of the motor and impeller shaft. While the axial shifting of the shaft 28 to move the washer 68 away from the sealing member 60 increases somewhat the compression of the spring 72 against the washers 73, ample provision for lubrication of the washers 73 is provided by the lubricant feed 15 channel 73' so that these washers act as a lubricated thrust bearing without substantial increase in friction and wear of the thrust parts.

Within the space between the walls 57 and 58 is provided a well 62 for the collection of any leakage water passing from the pump along the shaft 28. The well 62 is provided with a drain outlet passage 63 having a lower threaded end 64 to which a drain pipe may be attached or, as shown, a sealing plug 65 may be provided. Suitable 25 means are provided upon the shaft 28 within the area of the well 62 to prevent any possible leakage through the member 60 from continuing on along the shaft 28 and into the lubricated motor bearing 59. As shown, a ring 77 is fixed to the 30 shaft 28 and is provided with an outwardly extending flange 78 which is adapted to throw off by centrifugal force any water that may pass through the member 60. The extending portion 35 of the motor frame which comprises the disc-like walls 57 and 58, and the well 62, is open in its upper portion, to provide accessibility to the shaft 28 and permit the screws 38 which fasten the motor housing to the pump to be inserted and tightened. Strengthening and supporting 40 webs 80 connect the walls 57 and 58 at this upper open portion of the motor frame. A ring-like groove 81 is provided within the wall 58 and is positioned in line with the plane of the flange 78 so that any water thrown from the flange will be 45 collected within the groove 81 and will be carried into the well 62. Small quantities of water collecting here may be evaporated by the normal circulation of air through this space or, as mentioned, the well may be connected to a drain pipe. 50

The subatmospheric pressure existing adjacent the sealing washer 68 during operation of the impeller is created by the provision of spaced openings 80 in the impeller disc adjacent the hub portion 70, and auxiliary vanes 83 which are positioned on the disc portion 84 of the impeller on the side opposite to the water circulating vanes 85 assist in maintaining this subatmospheric pressure. As shown, the impeller vanes 83 are positioned within a close fitting ring-like groove 86 provided upon the adjacent face of the wall 58. The inner ends of the vanes 83 terminate in a ring 83' which is positioned concentrically and in close fitting relationship to the inner wall of the groove 86 which is formed by the peripheral edge of the face 65 15 of the sealing member 60. The openings 80 provide communication from the space adjacent the sealing washer 68 to the area adjacent the central opening 20 which is maintained under suction by the action of the impeller. A baffle, in 70 the form of a ring 87, mounted on the impeller adjacent the openings 80 serves as a deflector to direct away from the openings the flow of water induced by the impeller blades 85 and further increases the suctional pull through the openings 80 75

on the area adjacent the washer 68. Axial movement of the impeller and associated parts, to relieve the sealing washer from sealing contact during operation, is induced by the pressure of the water adjacent the offtake of the pump acting on the peripheral portion 88 of the rear face of the impeller. As shown, the impeller disc 84 is provided on the front face with circulating vanes 85 which extend substantially to the periphery of the disc 84. The opposite or rear face of the impeller carries the auxiliary vanes 83 which are positioned some distance in from the periphery of the disc thus providing an annular area 88 on the impeller disc. The impeller is shaped so that the area 88 lies closely adjacent the face of the web 58 with a small clearance space 89 therebetween which is open to the interior of the pump adjacent the peripheral edge of the disc 84. Water pressure created by the impeller vanes 85 acts on the relatively narrow annular portion 90 of the front face of the impeller extending between the vanes 85 and the periphery, and also acts on the oppositely positioned relatively larger area 88 on the rear face to produce an overbalancing pressure capable of moving the impeller to the left (as viewed in Fig. 5). The auxiliary vanes 83, like the circulating vanes 85, tend to create a circulation outwardly and by this circulation restrain the passage of water from the clearance space 89 which is under pressure towards the area adjacent the washer 68 which is under suction. The vanes 83 also restrain the passage of water towards the area of the sealing washer by provision of the close fitting relationship between the vane ring 83' and the peripheral face of the portion 75 of the sealing member 60. This close fitting relationship provides a clearance space which is considerably less than the area of the openings 80 and restrains the possible passage of water therethrough to an amount considerably less than the carrying capacity of the openings 80. Consequently the suction on the openings is effective to create the desired subatmospheric pressure. The vanes 83 therefore assist in maintaining the subatmospheric condition which restrains leakage along the shaft during operation, and aid in preserving the desired pressure differential between the rear and front portions 88 and 90 respectively of the impeller. Even though the sealing washer 68 is removed from its seat under these conditions, (as shown in Fig. 6), leakage past the sealing member 60 is prevented by the presence of subatmospheric pressure at this point. While the member 60 loosely receives the shaft 28 so as to avoid difficulties inherent in the provision of a third bearing for the motor shaft, nevertheless the spacing between the member 60 and the shaft is sufficiently small so as to prevent the ingress of objectionably large quantities of air from the open space between the walls 57 and 58 into the suction area adjacent the sealing washer 68.

For certain operating conditions, the pump and motor unit can be constructed so that the washer 68 remains in sealing contact with the sealing member 60 during operation of the impeller. This may be accomplished by so proportioning the parts of the impeller and the spring 72 that the axial thrust tending to remove the washer 68 from its seat during operation is insufficient to overcome the counterthrust of the spring 72 within the motor housing. By such suitable proportioning of the parts, the net resulting thrust tending to hold the washer 68 on its seat during operation can be regulated to any amount desired: for

example, the first mentioned axial thrust can be such as to substantially balance the counterthrust of the spring, or a greater pressure of contact of the washer 68 with the sealing member 60 can be provided. In such case, the members 60 and 68 are preferably made of suitable wear resisting materials which operate without objectionable friction, such as a hard stainless steel washer 68 and a graphite-bronze or durex sealing member 60. This construction provides an adequate sealing of the extended end of the motor shaft within the impeller housing, without the employment of the construction producing subatmospheric pressure adjacent the point of exit of the shaft from the pump housing and without the employment of stuffing boxes.

The discharge outlet 22 of the pump is provided with a threaded end 92 adjacent the opening 22' in the bottom wall of the tank 10 and the hollow sleeve attaching member 23 is provided with a flanged head 95 on the interior side of the tank 10. The extending threaded end 96 of the sleeve member 23 threadedly engages the portion 92 of the pump and upon drawing the sleeve 23 tight a water tight joint is provided between the tank 10 and the pump; suitable sealing gaskets 93 being included in the connection. The pump outlet 22 and the sleeve 23 are so proportioned that the inner diameters are alike, thus providing a free passage for the wash water from the pump to the wash arm which is mounted above the outlet in the sleeve 23. By attaching the pump housing to the tank in the manner shown a direct passage is provided from the pump discharge to the wash arm which is directly above the pump outlet. The wash arm 24 is supported for rotational movement upon a tubular member 98 which stands centrally aligned within the outlet end 22 of the pump discharge passage and projects therefrom into the tank 10. The lower end 99 of the hollow member 98 is threaded into a boss 100 which projects from a wall of the pump housing into the discharge passage of the pump and not only serves as a support for the wash arm structure but also provides a passage for the flow of rinse water which is carried to the wash arm structure through the hollow member 98. The boss 100 projects into the flow passage of the pump at a side thereof and is positioned so as to offer no obstruction to the free flow of wash water. The discharge passage of the pump, the boss, and the attached support member 98 are constructed so that a passage area of full pump capacity is provided in which there are no obstructions upon which waste matter flowing with the wash water may collect. The member 98 stands vertically aligned with the pump impeller, the boss is positioned directly above and adjacent the impeller, while the discharge passage is provided at a side of the boss and attached member 98. As shown, the wash arm 24 comprises a hollow member having a central hub portion 101 from which oppositely positioned arms 102 extend in which are provided suitable openings or slots 103 through which water is adapted to issue in the form of jets upon operation of the pump. Certain of the slots are inclined, as shown at 104, so that the wash arm may be rotated by the reactive force of the water issuing from the inclined slots.

The hub portion 101 of the wash arm carries bearings for free rotational movement of the arm on its supporting member 98, and is provided with an axially aligned bottom opening having a downwardly extending bounding flange 105 which

cooperates with the flanged head 95 of the pump attaching sleeve for passage of wash water from the pump to the wash arm. The upper face of the sleeve flange 95 and the bottom face of the wash arm flange 105 are machined so that they stand parallel, and adjustable means are provided in the bearing mounting so that the flange of the wash arm may be adjusted to a close running clearance with the sleeve flange to reduce strain leakage at this place. The bearing which carries the thrust load of the wash arm, and which also permits adjustment of the wash arm with respect to the sleeve flange 95, provides an axially aligned one point support for the wash arm structure. The supporting member 98 has pressed into it at the upper end a plug 98' which is threaded to receive a screw 106. The upper end of the screw 106, which is of some suitable material that may be properly hardened, is chamfered to provide a circular flat top surface of less diameter than the screw. The sides of the screw are flattened so that a wrench may be applied when it is desired to adjust it, and a lock nut is provided so that the screw may be held securely in adjusted position. The upper end of the hub portion 101 of the wash arm is provided with a cap 107 held thereon as by threaded engagement. A hardened bearing 108 is provided in the cap 107 on the axial line of the hub 101 and has a head portion 109 on the interior of the cap which is aligned to contact with the end of the screw 106. The hardened contacting faces of the members 106 and 108 provide a bearing whereby the weight of the wash arm and its associated parts may be supported for free rotational movement without appreciable friction. Further support of the wash arm for rotational movement is provided by the spaced sleeve-like bearings 110 positioned within the wash arm hub 101 and adapted to align the wash arm with respect to the upstanding supporting member 98. The pressure of wash water entering the wash arm through the large opening adjacent the fitting 23 tends to partially offset the weight of the wash arm carried at the point of engagement between the members 106 and 108 and provides a construction whereby the wash arm may be readily brought into rotation by the reaction forces as mentioned, and will continue to rotate freely for a period after the circulation of the wash water is discontinued. The wash arm assembly may be removed from the machine by merely lifting it from its supporting shaft 98. As the wash arm is maintained in its normal position only by gravity it will be apparent that if holes 103 should become clogged by extraneous matter in the wash water the wash arm will be lifted up by the pressure of water which will thereby be relieved between flanges 95 and 105. The interior of the wash arm is made readily accessible, as for the purpose of cleaning it, by the provision of removable end covers. Each end cover comprises a plate 111 pivotally supported at one side upon a screw 112 and having at the opposite side a slot 113 which in closed position is adapted to be held by a screw 112'. A portion of the rinse water distributing system is incorporated in the wash arm 24 so that an effective rinsing operation may be secured by taking advantage of the rotational movement of the wash arm produced during the washing operation. This arrangement makes it possible to provide a uniform distribution of rinse water even though the rinse water should be supplied at low pressure. As shown, pipes 114 are incorporated in the wash arm structure, and are provided with jets 115 through which rinse water may issue. The pipes 114 are connected to the hub portion 101 of the wash arm and are interconnected through a cored chamber 116 provided within the hub portion 101. The supporting member 98, as mentioned, is of tubular form and provides a passage for supplying rinse water to the pipes 114. A passage 117 is provided in the supporting boss 100 and connects with the cored chamber 116 through the hollow member 98 and a series of holes 118 positioned in the member 98 adjacent the chamber 116. The chamber 116 is shaped so that the rinse water pressure is uniformly distributed both upwardly and downwardly, hence there is no lifting force exerted on the wash arm by the rinse water as is provided by the wash water. The wash water, although supplied in large volume, is at a pressure not sufficient to displace the wash arm, while the rinse water may be supplied from a city water supply at a pressure sufficient to lift the wash arm from position if the forces were not balanced as described. Any tendency to lift the wash arm by leakage of rinse water along the shaft 98 adjacent the bearing 110 into the area beneath the cap 107 is eliminated by the provision of holes 119 which prevent an accumulation of pressure against the cap. A pipe 120 is threaded connected at 121 to the passage 117 and terminates at the opposite end in a fitting 122 attached to a suitable rinse valve 123 which is connected to a source of rinse water. A second pipe, designated 124, is also connected to the fitting 122 and passes through the wall of the tank 10 at 125, then extends upwardly on the interior of the casing to a position adjacent the top of the casing. Suitable rinse jets 127 are connected to a laterally extending portion 124' of the pipe 124 and are positioned within the top portion of the casing to direct streams of rinse water downwardly onto articles that may be positioned within the machine.

The supporting trackway 26 for the dish carrying racks comprises spaced horizontally extending bars 135 which are positioned at substantially the level of the supporting table and extend from the front to the rear of the machine. The forward ends of the bars 135 are provided with downturned lugs 136 which are attached to the interior of the tank 10 as by means of attaching screws 137. The rearward ends of the bars 135 are also provided with downturned lugs 139 which are suitably supported from the tank 10 as by means of screws 140. The lugs 139 serve as clamping means to position the resilient fingers 142 which extend upwardly from the position of attachment and are provided to form a resilient stop for the movable portion of the cover 15 when moved to open position. Upwardly extending flanges 144 having outwardly flaring forward ends 145 are positioned at the opposite sides of the bars 135 to provide lateral guides to properly position the dish carrying racks upon the trackway. The rearward ends of the members 144 terminate in inturned lugs 146 to which a tie bar 147 is connected. The tie bar serves as a limit stop for the dish carrying racks and prevents the racks from being inserted within the machine an amount sufficient to interfere with the operation of the movable cover. Plate guards are provided to prevent articles within the racks such as dishes and the like from interfering with the proper operation of the cover. As shown, spaced members 130 extend upwardly from the rear tie bar 147 of the trackway 26 and terminate at the

cross pipe 124' of the rinse water system to which they are attached by the clips 132. The plate guards 130 are curved so that they stand in spaced relation to the cover of the machine and not only serve to prevent dishes from contacting with the cover but also provide a support for the rinse pipe 124'. Being securely positioned between the trackway and the rinse pipe, the plate guards contact with any extending articles within the rack 10 as it is inserted and tilt these articles inwardly a sufficient distance to permit the movable portion of the cover to be readily moved, and to prevent damage to either rack articles or cover by contact upon movement of the movable cover.

15 In order that the momentum of the wash arm 24, created during the flow of wash water, may be effectively utilized to distribute the rinse water from the nozzles 115 a single control 150 is provided which is movable from a neutral position in opposite directions to operating positions for washing and rinsing operations respectively. By a single movement of this control the supply of wash water to the wash arm may be stopped and the supply of rinse water may be quickly 20 started with practically no time interval between the two operations. As shown, the control comprises a vertically extending rod 152 which is positioned on the exterior of the machine and is supported in suitable bearings for 25 rotational movement by an operating handle 151 to actuate the washing and rinsing mechanism. The control rod 152 stands adjacent a side wall of the cover on substantially the line of the axis of rotation of the cover. A bracket 30 153 is attached to the stationary cover adjacent the upper portion thereof and is provided with a suitable bearing for free rotational support of the control rod. Another bracket 153' extends from a lower portion of the machine and provides 35 additional support for the rod 152; the lower end of which has fixed to it a sleeve member 155 from which the operating mechanism is actuated. A collar 152' engages the rod 152 above the bearing of the bracket 153' and, with the 40 member 155 mounted below, serves to locate the rod vertically with respect to the machine. The rod 152 is loosely received in a bracket 154 on the tank 10; the bracket extending upwardly through the horizontal flange portion adjacent 45 the bottom of the stationary cover as shown. The bracket 153' in addition to supporting the arm 152 serves also to position the motor switch and rinse valve, so that they will be maintained in proper operating relationship. The sleeve 50 member 155 is provided with extending arms that are adapted to control the washing operation and rinse operations upon movement of the control rod. The washing operation is established by closing a switch to complete the circuit to the 55 motor 18. As shown, the sleeve 155 carries an arm 157 which provides pivotal support for a link 156 of adjustable length which is connected to the actuating member 158 of the switch 159. The link 156 has incorporated in it a universal 60 joint 156' which permits a desired freedom of movement while maintaining an operative connection at 158' with the switch actuating member. Suitable electrical connections are attached to the switch 159 to supply current through a 65 conduit 160 to the motor 18 for actuation of the pump.

70 A second arm, designated 162, is provided on the member 155 so that upon actuation of the control handle in one direction the arm 162 will contact with and provide longitudinal movement

of a rod 163 for actuation of the rinse valve 123. The rinse valve, as shown, has attached to it a pipe 164 connected to a suitable source of rinse water and has connected to it the fitting 122 to which the distributing pipes are attached. The 5 rod 163 is supported within spaced ears 165 forming part of the bracket 153'. A spring 168 is provided between the spaced ears 165, one end of which is adapted to bear against one of the supporting ears while the opposite end bears 10 against a washer 169 positioned upon the rod 163 by means of a locating pin 170. Movement of the control handle 150 and rod 163 towards rinse position compresses the spring 168 and thereby makes it necessary for the operator to intentionally hold the control 150 against the tension of the spring for as long a time as the rinsing operation is to continue.

15 The lug 172 is provided on the member 155 and is positioned to limit the travel of the control member 150 and associated parts when moved towards washing position. The bracket 153' has an extending lug 173 in which is provided a set screw 174 aligned to contact with the arm 172 and adjustable to limit the travel of the control 20 mechanism. The arms 157, 162 and 172 of the member 155 are spaced so that when the control handle and its associated parts are in neutral position the switch 159 will be in open circuit position and the rinsing valve will be closed. 25 Upon moving the control handle to washing position (which is counterclockwise from the position shown in Fig. 9) the arm 157 through the link 156 moves the switch member 158 to closed circuit position; this travel being limited by the arm 172. 30 Movement of the control mechanism toward washing position moves the arm 162 away from engagement with the rod 163, while movement of the control handle in the opposite direction to rinsing position swings the arm 162 to contact 35 with and move the rod 163 to actuate the valve 123. In moving from neutral to rinse position the arm 157 swings through a radius which produces very little movement in the switch member 158; the linkage in this case being carried across 40 a dead center position which maintains the switch member 158 in open circuit position. The switch shown is of a conventional tumbler type in which the switch contacts are resiliently held in either 45 "on" or "off" position, and in which some movement of the actuating member may occur without operating the switch contacts. In connecting the switch actuating linkage the parts are 50 adjusted so that when the control is in neutral position the switch member 158 is drawn away 55 from its limit of travel in the direction of the "off" position a distance sufficient to permit the linkage to pass through dead center position as the control is moved to the rinse position. This movement in the switch is not sufficient to operate 60 the switch contacts and consequently these are maintained in open circuit position. Movement of the control in a reverse direction from neutral position produces sufficient movement in the switch member 158 to close the switch contacts. This arrangement of operating parts permits a single control to be used for both the motor switch and the rinse valve while allowing 65 the required movement to open the rinse valve without effecting operating movement of the 70 switch.

As shown, the rinse valve 123 is supported from a lug 176 extending from the bracket 135'. The valve comprises a housing to which the rinse water supply and distribution pipes are connect- 75

ed, and is provided with a suitably packed stem 177 which stands aligned with the rod 163. The stem is adapted to actuate a valve plug 177' to control the flow of rinse water through the passage 178 within the valve. A dash pot is provided within the valve structure to prevent sudden closing of the valve with consequent hammering and strain in the rinse supply. The dash pot comprises a cup-like shell 179 which is attached 5 to the valve housing in alignment with the stem 177 and valve plug 177'. A piston 180 is provided which is adapted to slide within the portion 179 and which is provided with means such as the fingers 180' to interengage the valve plug. A 10 spring 181 is positioned between the dash pot piston 180 and the shell 179 and constantly urges the valve toward closed position. Upon releasing the valve stem 177 the valve is caused to close slowly by the action of the dash pot.

15 The attachment of the control lever 151 on the control rod is such that the position of the lever may be changed on the rod to provide a range of movement which will be convenient to the operator for a given location of the machine. The upper end of the control rod 152 is provided with a projecting key 152^a, while the hub portion of the lever 151 is provided with spaced key slots 151' so that upon assembly of the lever onto the rod the key may be inserted within the slot 20 which provides the proper location for the operating handle. The lever is further held to the control rod by provision of a set screw 150'. By positioning the control lever adjacent the upper portion of the cover it is located readily accessible 25 to the operator and is removed from the path of moving dish racks so that it will not interfere with the operation of the machine. An interlock is provided between the control mechanism and the movable portion of the cover to prevent operation of the wash water circulating system 30 when the movable cover member 15 is open. The interlock comprises a cam plate 185 operable with the control rod and adapted to engage and actuate a latch member 182 operable only when the cover is closed. The cam plate 185 is in the form 35 of a circular disc having a flat side 193, and having a control opening for passage of the control rod and spaced holes for the reception of screws 185' by which the disc is held to the bottom of the control lever. The spacing of the holes for the screws 185' is such that the cam will stand properly with respect to the latch when attached to the lever in any of the several positions that the lever may be attached to the control 40 rod, and will always be properly positioned for operation of the interlock. The latch member 182 is pivoted to the bracket 153, as by means of a pin 183, and is provided at one end with a finger like extension 188 which is adapted to engage the movable cover 15, and at the other end with a yoke like extension 190 which cooperates with the cam 185 for movement of the latch. The cutaway portion of the yoke comprises two curved sides 191 and 192 having a radius equal to the 45 radius of the circular portion of the cam plate. The axes of rotation of the cam 185 and latch 182 are positioned so that in neutral position of the cam the flat side 193 will contact with a flat end or lug 194 forming one side of the yoke 50 extension while the latch stands in unengaged position with respect to the cover member. As the control rod is moved in a clockwise direction (as viewed in Fig. 12) toward washing position the face 193 of the cam engages the face 194 of 55 the latch and causes it to move also in a clockwise direction. If the cover is closed no interference will be offered to movement of the latch finger 188 as a socket 186 is provided in the side wall of the cover 15 into which the finger is received. Radial movement of the latch ends 5 as soon as the flat face 193 passes from engagement with the end 194 of the latch; further movement of the control rod and cam being provided by the curved face 191 of the latch which is so positioned as to stand concentric with the curved 10 face of the cam when the latch is in engaged position thus permitting the control rod to continue in its movement to the position shown in Fig. 12. If, however, upon moving the control handle as mentioned during a time when the cover is not 15 closed the end 188 of the latch will strike the face of the cover side wall before the flat face 193 has passed the end 194 of the latch and further movement of the control arm will be prevented. At the end of the washing operation as the control 20 mechanism is returned to neutral position a second lug 196, forming part of the forked end 190, is engaged by the face 193 to return the latch 182 to unlatched position, as shown in Fig. 11. Further movement of the control handle, beyond 25 neutral position, brings the control mechanism to rinsing position, as shown in Fig. 13. The control arm and cam are free to move to rinse position without disturbing the latch. With the latch in neutral the curved face 192 stands concentric 30 with the curved portion of the cam 185 and the control lever can be moved to the position shown in Fig. 13 without moving the latch from unengaged position.

35 The latch 182 is proportioned to present a short effective lever arm to the control cam 185, while the lever arm terminating in the finger 188 is relatively of considerable length. This arrangement of parts permits the latch to withstand heavy loads at the control rod end, such as are encountered when an effort is made to operate the washing mechanism when the cover is open, without directing a heavy thrust against the cover wall. The parts of the latch are positioned with respect to the control cam so that, when moving 40 to washing position, a large angular movement of the latch results from a small angular movement of the cam until the face 194 passes from contact with the flat cam face 193 after which no further movement of the latch occurs while 45 the cam moves along the curved face 191 of the latch. The engagement in washing position is such that the latch is positively held in interlocking engagement with the cover socket 186 by contact of the latch face 191 with the curved face of 50 the cam. The total angular travel of the cam is large as compared to the latch movement. Consequently this linkage provides in effect a lost motion between the cam and latch whereby the control rod may be moved an amount sufficient 55 for proper actuation of the washing mechanism while moving the latch through but a short angular travel thus permitting the use of a shallow latch receiving interlock socket and long lever arm for the latch.

60 A supporting table is provided for the washing machine and comprises a rectangular frame 200 preferably composed of angle iron sections suitably joined, as by welding, and provided with strengthening gussets 202 adjacent the corners 65 from which the table legs 201 extend. The legs, gussets, rails 203, and a lower set of rails 200' which provide a frame for the support of a shelf below the table top, all being joined to provide a substantial supporting structure for the washing 70 75

machine. Spaced parallel rails 203, also of angular section, extend from front to rear of the frame 200 and are positioned with the horizontally extending legs of the angles in a plane with the top of the frame 200 and turned outwardly from one another. A connecting angle member 204 extends between the members 203 and, with the rear member of the frame 200, provides an opening 206 for reception of the washing machine. 5 Removable bars 207 are attached to the downwardly extending legs 208 of the members 203 and are removably held thereon as by means of screws 209. These bars provide ledges upon which outwardly extending flanges 10' of the tank 10 are 10 adapted to rest for support of the machine within the table. The rear wall of the frame between the members 203 is also provided with a removable bar 212 attached as by means of screws 213. This bar is not necessary for the support of the machine 15 in service but may be provided for additional support when it is desired to ship the machine assembled to its table. A cover 215, which may be made of sheet zinc or some other suitable material, covers the table framework to provide a 20 smooth working surface and has formed therein an opening 216 corresponding to the opening 206 of the framework. The rear edge of the top 215 is provided with an upwardly extending flange 217 which, for example, may rest against a side wall 25 of the room. This flange preferably stands up six to eight inches from the table surface while the flanges 217' which enclose the remaining sides of the table top extend upwardly to a height of about two inches. An upwardly extending flange 218 30 is provided adjacent that portion of the opening 216 which will be covered by the stationary portion 13 of the cover member, while a downturned flange 219 is provided to engage a depression provided in the edge of the tank 10 adjacent that portion covered by the movable part 15 of the casting. 35 The cover in assembled position presents a slightly dished surface which is highest adjacent the rim of the table and slopes downwardly, an amount sufficient to provide drainage, toward a low point adjacent the downturned flange 219. 40 The washing machine is readily assembled to the supporting table by being lifted upwardly through the opening 216 after which it is held in place by attachment of the supporting strips 207. 45 When the washing machine is to be assembled within this supporting structure the cover portions 13 and 15 are removed as a unit from the machine by removing the attaching screws 221, the tank 10 and associated parts are then lifted 50 upwardly through the opening 216 until the upper edge of the tank contacts with the table cover 215 at the front edge of the washing machine. Upon moving the machine upwardly through the opening 216 into proper position the strips 207 and 55 212, which have previously been removed, may be reassembled so that the flange 10' will rest upon these strips. The cover portions 13 and 15 may then be reassembled. The interengagement of the tank flanges 10' with the table structure effectively positions the washing machine so that even 60 when in transit assembled to the table it is securely held in place. The strips 207 and 212 prevent movement of the machine downwardly with respect to the supporting table, and the engagement of the overlapping table cover 215 with the front upper ledge of the tank as well as engagement of spaced lugs 220 which extend from the rear exterior face of the tank and underlie the strip 212 serve to prevent upward movement of 65 the tank. 70 75

The attachment of the cover portions to the tank 10 and the assembly of the machine to the table is such that water cannot pass between the tank and the table opening 216, and during operation water may not splash from the tank adjacent the line of contact with the covers 13 and 15. 5 As shown, the stationary portion 13 of the cover is removably attached to the top edge of the tank 10 by means of screws 221 and is spaced therefrom by the provision of strips 222 which provide a 10 seal between the lower edges of the cover 13 and the tank top. At the rear of the machine the cover 13 terminates in a portion 223 which extends downwardly a short distance within the tank 10 then turns back upon itself and extends 15 upwardly, then outwardly as at 224 at the height of the sealing strip 222 above the top edge of the tank 10, then downwardly as at 225 to overlie the flange 218 of the top 215. The downturned flange 225 extends throughout the length of the stationary cover and overlies the table flange 218 so that any liquids spilled adjacent the exterior of the machine are directed onto the table top and are drained by the sloping top of the table into the tank at the front side. The movable portion 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

which is supported by the lower frame 200' provides a storage space for dish racks which are not being used.

The pump shown in Figs. 5 to 8 forms the subject matter of my Patent No. 1,967,316, granted July 24, 1934.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A washing machine assembly of the character described comprising in combination, a supporting table having a table top provided with an opening therein, a washing machine having an open top tank removably carried by said table 10 opposite said opening with the level of said open top tank at substantially the level of said table top, and having a cover removably fastened to said tank, interfitting flanges between a portion of said washing machine and said table top providing drainage from the cover onto said table top and restraining leakage through the said opening through the table top, and additional interfitting flanges between said table top and said open top tank providing drainage from said 30 table top into the interior of said tank.

2. A washing machine assembly of the character described comprising in combination, a supporting table having a table top provided with an opening therein, a washing machine having an open top tank supported by said table opposite said opening with the level of the open top tank at substantially the level of said table top and having a cover, rack supporting means carried by said tank at substantially the level of said table 35 top, washing mechanism within said tank, said cover including a stationary portion over said open top tank provided with a front rack receiving opening, and a movable portion telescopically fitted with the stationary portion and pivoted thereto for exposing and closing said front rack receiving opening, interfitting flanges between the said stationary cover portion and the said table top about the sides and back of said opening through the table top providing drainage 45 onto the said table top and restraining leakage through the said opening through the table top, and interfitting flanges between said table top and the front side of said open top tank providing drainage from said table top into the interior 50 of said tank, said table top being inclined to direct liquid thereon toward the front side of the said open top tank and into the said tank.

3. A unitary washing machine assembly of the character described, comprising in combination, a supporting table having supporting legs, a table top carried by said legs, said table top having an opening therein adjacent the rear side thereof, a washing machine having a washing tank removably suspended from said table opposite said opening, rack supporting means stationarily carried by said tank at substantially the level of said table top, said washing machine also having a cover removably carried by said tank for enclosing said tank and having a portion movable to provide a front opening for insertion of racks into and withdrawal of racks from the said washing machine, said table top being provided with a rack supporting space on the exterior of the washing machine and in advance of the said front opening sufficient in extent to receive a rack, whereby

a rack may be readily slid from the said supporting space of the table top into the washing machine and onto the rack supporting means, and may be readily slid from the rack supporting means out of the washing machine onto the said supporting space of the table top, and means for draining said supporting space of the table top into the interior of said tank.

4. A unitary washing machine assembly of the character described comprising in combination, a supporting table having supporting legs, a table top carried by said legs, said table top having an opening therein adjacent the rear side thereof, a washing tank removably suspended from said table opposite said opening, rack supporting means carried by said tank at substantially the level of said table top, and a cover removably carried by said tank and providing a washing compartment, said cover having a portion movable to provide a front opening for insertion of racks into and withdrawal of racks from the said compartment, said table top being provided with a rack supporting space on the exterior of the tank and in advance of the said front opening sufficient in extent to receive a rack, whereby a rack may be readily slid from the said supporting space of the table top into the compartment and onto the rack supporting means, and may be readily slid from the rack supporting means out of the compartment onto the said supporting space of the table top, said table top also being provided with rack supporting spaces at opposite sides of said tank sufficient in extent to receive racks thereon, whereby a rack may be slid from the supporting space at one side of said tank to the supporting space at the front of the tank and then into the compartment, and may then be withdrawn from the said compartment onto the said front supporting space and be then slid to the supporting space at the opposite side of the tank.

5. A washing machine comprising an open top tank, an outwardly extending flange on said tank, a supporting frame for said tank having an opening therein for reception of said tank, supporting members detachably connected to said supporting structure and adapted to underlie said flange to removably suspend the tank from said supporting frame, and an outward projection on said tank beneath at least one of said detachable supporting members to restrain upward movement of said tank from its suspended position.

6. In a washing machine, an open top tank, washing means therein, a cover for said tank adapted to move from a position enclosing the open top of said tank to a position adapted for the insertion of a rack of articles to be washed into said tank, rack supporting means within said tank adapted to support the said rack of articles in the said tank in position to be enclosed by said cover, and a guard member positioned above said rack supporting means at the height of projecting parts of articles in said rack, said guard member being within but adjacent the path of movement of said cover to prevent articles in the said rack from being moved into the path of movement of the said cover.

7. In a washing machine, an open top tank, washing means therein, a cover for said tank including a stationary portion and an interfitting movable portion, said stationary portion comprising spaced parallel end walls and a connecting curved side wall, said movable portion comprising spaced parallel end walls and a connecting curved side wall receivable within said stationary portion.

tion and movable from a position in which the movable portion is telescoped within the stationary portion to an extended position providing a closure for said washing machine tank in which 5 parts of the cover portions still overlap, rack supporting means within said tank positioned substantially at the level of the open top of said tank and adapted to support a rack of articles in the said tank in position to be enclosed by said cover, 10 means for limiting the extent of insertive movement of the said rack to prevent the rack from being moved into the path of movement of the movable cover portion, and a plurality of spaced guard members extending upwardly in substantially parallel relationship across the rear of said washing machine, each guard member comprising a curved bar extending upwardly above the said rack supporting means and rack carried thereby within but adjacent the path of movement 15 of the movable cover portion to prevent articles carried by the rack from protruding into the path of movement of the said movable cover portion.

8. In a washing machine, a washing compartment having a movable cover therefor, a rack supporting structure adapted to support a rack of articles to be washed in position in said washing compartment to be enclosed by said cover the path of movement of said cover being adjacent articles supported in a rack mounted on said rack supporting structure, means for distributing wash water upon the rack of articles within said compartment, means for distributing rinse water upon the rack of articles within said compartment including a rinse water supply pipe positioned above said rack supporting structure, and a guard member extending from said rack supporting structure to said rinse pipe and intermediate the path of movement of said cover 30 and the position of articles in the rack to limit the position of articles within an inserted rack to prevent the articles from protruding into the path of movement of said movable cover.

9. In a washing machine, a washing compartment, a movable cover member therefor adapted to move from a closed position closing said washing compartment to an open position, means for supplying washing fluid to said washing compartment, a movable control member for said washing fluid supply means, and a latch member for interengagement with the cover member and the control member to prevent opening the cover when the control member is in position for supplying washing fluid and to prevent movement of the control member to the position for supplying washing fluid except when the cover is closed, said latch having a cover engaging portion for holding the latch in locking engagement with the control member when the cover is open to prevent movement of the control member to the position for supplying washing fluid and having a portion operated by the control member for moving the latch into locking engagement with the cover when the cover is closed and the control member is moved to the position for supplying washing fluid.

10. In a washing machine, a washing compartment, a movable cover member therefor adapted to move from a closed position closing said washing compartment to an open position, fluid supply means for supplying washing fluid to said washing compartment, a movable control member for said fluid supply means, a latch member operable as an interlock between said cover member and said control member, said

latch member having a portion held by the cover in engagement with the control member when the cover is open to prevent actuation of said control member to supply washing fluid to said washing compartment, said cover member having a recessed portion adapted to move with said cover member to a position opposite said latch member when said cover is moved to closed position to provide for movement of the latch member and actuation of the control member 10 to supply fluid to the washing compartment, said latch member being moved upon actuation of the control member to supply washing fluid to the washing compartment into interlocking engagement with the said recessed portion of said cover member to prevent opening of said cover member in such fluid supplying position of the control member.

11. In a washing machine, a washing compartment, a movable cover member therefor adapted to move from a closed position closing said washing compartment to an open position, fluid supply means for said washing compartment, a movable control member therefor, a pivotally mounted latch member directly operative between said cover member and said control member when said cover member is in open position to provide an interlock to prevent actuation of said control member such as to supply fluid to said washing compartment, said latch member comprising an arm on one side of the pivotal mounting adapted to cooperate with and engage said cover member, and a forked arm on the opposite side of the pivotal mounting adapted to cooperate with and be operatively engaged by said control member, said cover member having a socket portion movable therewith to a position opposite said first mentioned arm of the latch member when the cover member is moved into closed position to provide for movement of the 40 latch member into said socket portion so that the control member may be moved to supply fluid to the washing compartment, the said first mentioned arm of the latch member being moved into interlocking engagement with the said 45 socket portion of the cover member as the said latch member is swung about its pivotal mounting by the operative engagement of the control member when the control member is actuated to supply fluid to the washing compartment. 50

12. In a washing machine, a washing compartment, a movable cover member therefor having latch receiving means thereon, wash water supply means for said washing compartment, rinse water supply means for said washing 55 compartment, a single control member therefor movable in opposite directions from a neutral position and having latch receiving means thereon, operative interconnections between said single control member and said wash water supply means and said rinse water supply means for actuating said wash water supply means and said rinse water supply means respectively, a separate latch member directly operative as an interlock between said cover member and said control member, said latch member having a portion held by the cover in engagement with the latch receiving means of the control member when the cover is open to prevent actuation of said control member such as to supply wash water 60 to said washing compartment, said latch member being movable by the control member in closed position of said cover into interlocking engagement with said latch receiving means of the cover member when said control member is 75

moved into position to supply wash water to said washing compartment.

13. In a washing machine, a washing compartment, wash water supply means therefor, 5 rinse water supply means therefor, a single control means movable from a neutral inoperative position in opposite directions to operative positions for control of said wash and rinse water supply means respectively, and a linkage permanently and positively connecting said control means and one of said supply means including a pivotally interconnected arm and link, said linkage allowing movement of the control means to operative position in one direction as the said 10 pivotally interconnected arm and link move from one side of dead center position to the other side thereof without substantial movement of the said supply means positively connected thereto so as to avoid actuation of said supply means, 15 said supply means being actuated upon movement of the control member in the opposite direction from neutral position.

14. In a washing machine, a washing compartment, a movable cover member therefor, 25 fluid supply means for said washing compartment, a manual control member movable to actuate the fluid supply means, interlock actuating means on said control member, a movable interlock operative between the movable cover member and the interlock actuating means of the 30 control member, said interlock comprising a lever having a relatively short effective lever arm operatively engaged by said interlock actuating means and receiving the moving force transmitted from the manual control member when force is applied to the latter to actuate the fluid 35 supply means, and a relatively long effective lever arm adapted to engage the cover member when in open position to prevent movement of said manual control member to actuate the fluid supply means whereby the pressure of said long lever arm against said cover is reduced for a given force transmitted from said manual control member to said short lever arm.

43. 15. In a washing machine, having a washing compartment, a movable cover therefor having an interlock receiving portion, fluid supply means for said washing compartment, and control means therefor including an operating member; a cam member movable by said control means, a separate movable interlock member positioned adjacent said cover for operation by said cam into interfitting engagement with the said interlock receiving portion of said cover, so that upon movement of the control means to supply fluid to the washing compartment the interlock is moved into interfitting engagement with the said interlock receiving portion of the cover member, said interlock member having a surface portion positively 50 engaged by said cam to effect movement of the interlock member, and another portion of the surface of the interlock member being concentric with a cooperating portion of the surface of the cam to provide for additional movement of the control means and cam without movement of the interlock member.

60. 16. In a washing machine, having a washing compartment, a movable cover therefor, fluid supply means for said washing compartment, 70 and control means therefor including a control handle; a control cam detachably connected to said control handle, an interlock member operable by said control cam and positioned to be moved by said cam into interlocking engagement 75 with said cover when said control handle is actu-

ated to supply fluid to said compartment, means for attaching said control handle to said control means in different angular positions, and means for attaching said control cam to the control handle to insure the attaching of the control cam 5 in proper operative position relatively to said interlock member irrespective of the attached position of the control handle on the said control means.

17. In a washing machine, an open top tank, a 10 cover member for enclosing said open top tank including a stationary portion having a front opening and a movable portion in telescoping relationship within said stationary portion and adapted to close the said front opening of the 15 stationary portion, fluid supply means for said washing machine, control means therefor including a control shaft extending upwardly along the side of said cover member, a control handle for said shaft positioned adjacent the upper portion 20 of said cover member, an interlock movably mounted on said machine adjacent said cover member, and operative interconnections between said interlock and said control means to move 25 said interlock into interlocking engagement with the said movable cover portion in closed position of said movable cover portion when said control means is moved to actuate said fluid supply means, said movable cover portion having an interlock receiving portion movable with said cover portion 30 within the stationary cover portion as the movable cover portion is moved to open position.

18. In a washing machine, a washing compartment, a cover member therefor, fluid supply means for said washing compartment, control 35 means for said fluid supply means including a control member movable from a neutral position to a fluid supplying position, a cam actuated by said control means, an interlock member operatively engaged and actuated by said cam, said 40 interlock being positioned to operatively engage said cover member in open position of the cover member to prevent actuation of said control member from neutral position to said fluid supplying position when said cover member is open, 45 said cam having a curved operating surface and a flat operating surface, said interlock member also having a curved cooperating surface and a flat co-operating surface, the said flat surfaces of the cam and interlock member being in cooperating frictional engagement in neutral position of said control means, whereby force applied to said control member tending to move the control means to the fluid supplying position when the said cover member is open and which is resisted by the contact of the interlock member against the cover is 50 partially dissipated in frictional resistance between the said cooperating flat surfaces to thereby reduce the pressure of contact of the interlock member against the cover. 55

19. In a washing machine, a washing compartment, a cover member therefor, fluid supply means for said washing compartment, control means for said fluid supply means including a control member movable from a neutral position 65 to a fluid supplying position, an interlock member positioned to operatively engage said cover when said cover is open, operative connections between said control means and said interlock to effect movement of said interlock member upon 70 movement of said control member, and to prevent actuation of said control member to supply fluid to said washing compartment when said interlock member engages said cover in open position of the cover, said cover having an inter- 75

lock receiving recess positioned so as to move opposite said interlock member when the cover is moved to closed position, said interlock being moved in closed position of the cover upon actuation of the control member to fluid supplying position into interlocking engagement with said recess of the cover member, said operative connections between said control means and said interlock including a lost motion device to provide for a relatively small effective movement of the interlock member into interlocking engagement with the said recess upon a relatively larger movement of the control member of the said control means upon movement of the control member and control means into fluid supplying position.

20. In a washing machine, a washing compartment, a cover member therefor, fluid supply means for said washing compartment, control means for said fluid supply means including a control member movable from a neutral position to a fluid supplying position, a cam member operatively connected to said control means to be actuated thereby, a pivoted interlock member operatively engaging said cam member to be moved thereby, said interlock member being positioned to move into interlocking engagement with said cover to maintain the cover closed when said control member is moved to said fluid supplying position, said interlock member having spaced fingers adapted to be engaged by said cam upon movement of the cam and control member in opposite directions, said interlock member having a cam concentric surface between said fingers to provide for additional movement of said cam and control member without corresponding movement of said interlock member.

21. In a washing machine, a washing compartment and a reservoir, said washing compartment 40 draining into said reservoir, a pump having a volute housing provided with a centrally arranged intake communicating with said reservoir and a tangentially arranged pump outlet communicating with said washing compartment, an impeller 45 within said volute pump housing, rinse water discharge means within said washing compartment, a rinse water supply conduit positioned within said pump outlet, said pump housing having a rinse water supply passage formed therein above 50 said impeller and communicating with said rinse water supply conduit at a position adjacent and freely accessible from the outlet where it communicates with the washing compartment, said supply passage extending from the wall of said 55 pump housing so as to form a continuation of the volute housing of the said impeller, the lower portion of the said tangentially arranged pump outlet being positioned at the side of said rinse water supply passage and conduit whereby the discharge of the pump outlet from the immediate 60 vicinity of the impeller is substantially unimpeded, the upper portion of the pump outlet surrounding the said rinse water supply conduit.

22. In a washing machine, a washing compartment, a reservoir adapted to contain a quantity of wash water, said washing compartment draining into said reservoir, said reservoir having a conical seat in a wall thereof, an overflow pipe bodily removable from said reservoir having a 65 conical end removably positioned in the said conical seat in the wall of said reservoir, wash water spraying means for said washing compartment, a pump for supplying wash water to said spraying means, an intake for said pump extending into 70 said reservoir, said pump intake being formed

with an outer guiding groove for guiding said overflow pipe into assembled position in the said conical seat.

23. A washing machine assembly of the character described, comprising in combination, a 5 supporting table having a table top provided with an opening therein, an upstanding flange on said table about only a portion of the edge of said opening, a washing machine having an open top tank suspended from said table opposite said 10 opening, means carried by said table for supporting the machine with the level of said open top tank at substantially the level of said table top, rack supporting means stationarily mounted on said assembly at substantially the level of 15 said table top, a cover carried by said assembly for enclosing a rack within the machine when positioned on said rack supporting means, and a flange carried by said cover and overlying said upstanding flange of the table top to provide 20 drainage from the cover onto the table top, said table top having a flange overlying said open top tank to provide for draining into said open top tank about a portion of the edge of said opening in the table top which is unprovided with the 25 said upstanding flange.

24. A washing machine assembly of the character described, comprising in combination, a supporting table having a table top provided with an opening therethrough, a washing machine 30 having an open top tank suspended from said table opposite said opening, means carried by said table for supporting the machine with the level of said open top tank at substantially the level of said table top, rack supporting means 35 stationarily mounted in said tank at substantially the level of said table top, a cover over said open top tank, including a stationary exterior part, and a pivotally mounted interior part telescopically fitted within said exterior part and movable to provide an opening through which a rack may be slid from said table top onto said rack supporting means and then enclosed within said machine, an upstanding flange on said table top about the portion of the edge of said 40 opening along which said stationary exterior cover part extends, a cooperating flange on said exterior cover part overlying the said table flange to provide draining from the exterior of the cover onto said table top, and a downwardly extending flange on said table top overlying the edge of said open top tank about another portion of the edge of said opening for draining liquid from 45 said table top into said tank.

25. In a washing machine, the combination 55 with a tank, washing means therein, a cover for the tank including an outer stationary portion and an inner movable portion telescopically fitted within said stationary portion, and rack supporting means for supporting a rack of articles 60 within the machine in position such that the inner movable cover portion is adjacent articles in the rack, of a guard member positioned within and adjacent the path of movement of said inner movable cover portion and above said rack 65 supporting means at the height of articles within said rack to prevent articles in the said rack from moving into the path of movement of the said movable cover portion.

26. In a washing machine, a washing compartment, wash liquid supply means therefor including a motor operated pump and a switch for controlling the supply of electrical energy to said motor, rinse liquid supply means therefor, a single manual control member, and operative in 70 75

58

2,063,746

13

- terconnections between said single manual control member and said motor switch and said rinse liquid supply means such that movement of said manual control member in one direction from a 5 neutral position closes said switch to supply wash liquid to said compartment, and movement of said manual control member in another direction from said neutral position actuates said rinse liquid supply means to supply rinse liquid to said 10 compartment, said operative interconnections including a permanent and positive interconnection between said control member and said switch comprising a pivotally interconnected arm and link movable from one side of a dead center position to the other side thereof as said manual 15 control member is moved from neutral position

in said other direction to supply rinse liquid to said compartment, and without sufficient movement of said switch positively connected thereto such as to close said switch.

27. The combination of a table top containing 5 an opening and having an upturned flange around part of the opening and a downturned flange around the remainder of the opening, and a partially enclosed, washing machine tank in the opening, having, on its enclosed part, a down-turned flange overlapping and lying outside of the upturned flange of the table and, at the upper edge of its open part, an upturned flange overlapping and lying outside of the downturned flange of the table top. 10 15

DAVID A. MEEKER.
